United States Patent Office

Des. 222,315

Patented Oct. 12, 1971

222,315

TOOL KIT

Adolph Abraham, 1357 Barry Ave.,
Chicago, Ill. 40657

Filed Aug. 20, 1970, Ser. No. 24,595

Term of patent 14 years

Int. Cl. D3—99

U.S. Cl. D87—1

FIG. 1.

FIG. 2.

FIG. 3.

FIG. 4.

FIG. 5.

FIG. 6.

FIG. 1 is a perspective view of a tool kit showing my new design;

FIG. 2 is a top plan view;

FIG. 3 is a view in end elevation;

FIG. 4 is a perspective view thereof with the covers removed;

FIG. 5 is a top plan view of FIG. 4; and

FIG. 6 is a transverse vertical section, being taken on the line 6—6 of FIG. 4.

I claim:

The ornamental design for a tool kit, as shown and described.
